United States Patent

Des. 240,304

Patented June 15, 1976

240,304

LIGHTER

Guy Neyret, Francheville, Rhône, France, assignor to
Établissements Génouil & Cie, Vénissieux, Rhône,
France

Filed Aug. 30, 1974, Ser. No. 502,230

Claims priority, application France Mar. 13, 1974

Term of patent 14 years

Int. Cl. D27—05

U.S. Cl. D27—43

FIG.1

FIG.2

FIG.3

FIG.4

FIG.5

FIG.6

FIG. 1 is a top perspective view of a lighter showing my new design;

FIG. 2 is a side elevational view thereof;

FIG. 3 is a side elevational view thereof from the side opposite that shown in FIG. 2;

FIG. 4 is a top plan view thereof;

FIG. 5 is an end elevational view thereof from the right of FIG. 2; and

FIG. 6 is an end elevational view thereof from the right of FIG. 3.

The bottom of the lighter is plain.

I claim:

The ornamental design for a lighter, as shown and described.
